CLAIM

The ornamental design for a display screen with graphical user interface as shown and described.

DESCRIPTION

FIG. 1 is a front view of a display screen with graphical user interface, showing my new design; and, FIG. 2 is a front view of a display screen with graphical user interface showing my new design.

The outermost broken line rectangle depicts a display screen. The remaining broken lines depict portions of the graphical user interface. All broken lines form no part of the claimed design.

1 Claim, 2 Drawing Sheets

FIG. 1

FIG. 2
